CENTRAL SHANK REAMING DISK BIT

Filed Nov. 8, 1924

INVENTOR:
FREDERICK W. HILD
BY.

Ford & Hause
ATTORNEY.

UNITED STATES PATENT OFFICE.

FREDERIC W. HILD, OF LOS ANGELES, CALIFORNIA.

CENTRAL-SHANK-REAMING DISK BIT.

Application filed November 8, 1924. Serial No. 748,565.

This invention relates to bits, and it relates particularly to rotary disk bits which are used in the drilling of oil wells.

A well is drilled by means of a drill bit secured to the lower end of a drill pipe. The drill pipe is arranged to be rotated by a rotary table situated at the surface of the well, this being effective in rotating the bit and sinking the hole. Rotary disk bits, to 5 which this invention closely pertains, are used extensively in preference to the fishtail types of bit, this being because disk bits are of a much longer life than fishtail bits. The long life of disk bits is due to the fact that 10 the disks thereof may rotate on their own axes as the complete bit rotates. Substantially one-fourth of the perimetric cutting edge of the disks is working at one time, so that it may naturally be assumed that the 15 cutting edge will last much longer in this type of disk than the cutting edge of other types of bit.

These disk bits, however, have their disadvantages.

25 In the first place, difficulty is present because of the inability (in the present designs) to provide rugged enough bearing members for the disks. Logically, this inability increases the danger of the losing of a disk 30 due to the breakage of a bearing pin, or the bending of bearing pins which may impede the working progress of the bit, and necessitates elevating it to the surface to replace the damaged parts, thus consuming much 35 time and being expensive.

It is an object of this invention to overcome the above deficiency in the present types of disk bit by providing a bit which is so designed as to permit the use of very 40 rugged bearing or disk supporting members.

It is another object of this invention to provide a unique means for retaining the bearing members in place, this retaining means being so constructed and so situated 45 that external impediments cannot dislodge or loosen it.

Another disadvantage of the present types of disk bit is the tendency thereof to bore corkscrew or crooked holes, the undesirable- 50 ness of a crooked or corkscrew hole being obvious as it places a preponderance of strain on the drill pipe and bit, necessitates reaming, and makes it difficult to install a well casing. The corkscrewing of a bit of 55 this character may have its source in the

fact that disk bits have no guiding or centralizing means and are, therefore, free to walk around or to follow a path offering the least resistance.

It is a further object of this invention to 60 provide in a disk bit of this character a means for guiding the bit and thereby prevent the drilling of crooked and corkscrew holes to a great extent.

Another condition of defective operation 65 of disk bits is the forming of cores. Since the disks are spaced apart from each other a relatively substantial distance, it is obvious that the material between the disks is not subjected to the cutting action thereof. 70 A central core, therefore, forms as the bit progresses downwardly. The core will soon encounter the central support and in hard formations may prevent further progress 75 of the bit. In any case, a rising core may deflect the bit and cause a crooked hole.

It is a still further object of this invention to provide a means for cutting away the core as it forms and in this manner provide a disk bit in which there is less danger of 80 drilling a crooked hole.

It is another object of this invention to provide a disk bit having in combination a means for reaming the hole to proper size.

It is a still further object of this invention 85 to provide in a disk bit of the character described means for insuring rotation of the reaming means or elements on their own axis.

Other objects and advantages of the in- 90 vention will appear in the following description.

Referring to the drawings which are for illustrative purposes only,

Fig. 1 is an elevational view of a disk bit 95 embodying the features of my invention, this view being sectioned near the lower portion thereof to facilitate the showing of the improved form of bearing members and the novel means employed for securely retaining 100 the bearing members in place.

Fig. 2 is an elevational view taken at right angles to Fig. 1, a small portion thereof being sectioned to clearly show the construction of the reaming elements of the bit.

Fig. 3 is a section taken substantially as indicated by the line 3—3 of Fig. 2.

Fig. 4 is a section taken substantially as indicated by the line 4—4 of Fig. 1.

Fig. 5 is a bottom plan view of Fig. 1. 110

this view clearly showing the position of the core-removing means employed in conjunction with other features of the bit.

In the drawings the numeral 11 represents 5 the body of the bit, this body being comprised of a shank portion 12 having a threaded pin 13 at the upper end thereof for securing the bit to the lower end of a string of drill pipe. Formed adjacent and below 10 the shank portion 12 is a central portion 14, from which there depends a central lower leg 15.

The boring means provided in this invention may consist of bearing members 17 and 18 which have cylindrical bearing portions 19 which are flattened at 20, as clearly shown 15 in Fig. 4, there being formed at the outer end of the bearing portions 17 and 18 head portions 21. The bearing members 17 and 20 18 are each, as shown in Fig. 4, arranged to be inserted in an opening 23 in the depending leg 15, these pins being inserted from opposite sides of the leg 15 and being positioned so that the flattened faces 20 thereof 25 are in contact with each other. Rotatably disposed on the extending portions of the bearing surfaces 17 and 18 are boring disks 25 and 26, which are situated between the heads 21 and wear plates 28. The bearing 30 members are arranged to be secured in place by means of a central locking pin 30 which extends into an axial opening 31, provided in the central depending leg 15. In the contacting faces 20 of the bearing members 35 17 and 18 there are formed semi-circular grooves 32 which when the pins are installed, as shown in Fig. 4, co-operate to provide a circular opening 33 through which the locking pin 30 extends and serves to lock 40 the members 17 and 18 against movement in any direction. The locking pin 30 is arranged to be held in place in the axial opening 31 by means of a threaded portion 34 which threads into the lower end of the depending leg 15, as is clearly shown in Fig. 1. 45 By the construction illustrated, it is possible to provide much larger bearing surfaces than is possible in any of the previous types of disk bit. It is also possible to place the centers of the bits in approximate alignment, thereby permitting the use of fairly large 50 disks.

Reaming and aligning means provided by the invention may be in the form of bearing 55 members 40 and 41, having semi-cylindrical portions 42 which are flattened as shown at 43 in Fig. 3, these cylindrical portions being inserted in the opening 44 provided in the central portion 14 of the body 11 in such a 60 manner that the flat faces 43 are in contact with each other. The bearing members 40 and 41 are extended into the opening 44 in the central portion 14 from opposite sides thereof, similar to the bearing members 17 65 and 18, but substantially at right angles to

the bearing members 17 and 18. Formed at the outer end of the cylindrical portions 42 are bearing portions 46 which extend outward and upward, as clearly shown in Fig. 2, so as to be non-perpendicular to the axis 70 of rotation of the bit A—A (Fig. 2). At the outer ends of the bearing portions 46 there are provided cylindrical heads 47. In the flat portions 43 there are provided semi-circular grooves 48 which cooperate to provide a cylindrical opening 49, through which the extreme upper end of the locking pin 30 extends. In this manner, the locking pin 30 is made to lock both the boring bearing members 17 and 18 and the reaming bearing members 40 and 41 in place. Rotatably 75 on the bearing portions 46 are reaming members in the form of disks 51, which are situated between the heads 47 and wear receiving washers 52.

By inspection of Fig. 2, it will be seen that, due to the presence of the slant in the bearing portions 46, the reaming disks 51 will be made to lie non-perpendicular to the axis of rotation A—A. In other words, the reaming disks 51 converge relative to each other at the upper portions thereof. It will be seen that this construction allows rugged bearing members large bearing surfaces and large disks, as does the construction employed for supporting the boring disks. By utilizing a unitary means for securing both the boring and the reaming bearing members in place, it is possible to provide a disk bit having fewer parts, thus allowing more 100 rugged construction and providing a device which is much simpler to assemble than the present bits. Rotation of the reaming disks is assured by the disposal of these disks in non-parallel alignment to each other and to 105 the axis of rotation A—A.

The reaming disks are placed at right angles since such disks, when in contact with only the side of the hole, do not rotate and flat places form thereon which are obviously 110 disadvantageous. The tractive effort of the disk to rotate on its own axis depends upon the angular relationship of the disk with respect to the surface against which it cuts or rides. When a force is applied to the 115 periphery of a disk at right angles to the extension of the axis thereof, or, in other words, in a tangential direction, the rotative tendency thereof is at its maximum. When the force is applied against the periphery of a disk in the same direction as the extension of the axis of the disk, the rotative tendency incurred in the disk is at its minimum. From the drawing it will be seen that force exerted against the periphery of 120 the reaming disk 51 is applied in a direction which is perpendicular to the axis of rotation A—A of the bit. It will be seen that were the disks mounted perpendicular to the axis A—A, the rotative tendency would be 125 130

nothing. However, by mounting the disks at an angle relative to the axis A—A, the rotative tendency is magnified according to the angle.

5 On the head portion 60 of the securing pin 30 cutting blades 61 may be formed, these cutting blades being a means for removing or cutting away a core, indicated at 62, as it forms, so that no interference to 10 the progress of the drill will be encountered. It will be seen that the friction against these blades produces a tendency to tighten the threads 34 of the pin 30 and, therefore, assures that the members 40 and 41 will not 15 be dislodged. It will be seen that as the blades wear away they may be readily and easily re-sharpened because of the possibility of removing the complete pin 30. When the blades wear sufficiently to justify 20 replacement, this may be cheaply done because of the simple and inexpensive design of the locking pin 30.

Lubricating fluid may be supplied through a central lubricating passage 64 which branches at 65 to avoid the bearing members 40 and 41 and has openings 67 for supplying fluid to the boring disks 25 and 26. Lubricating mud may be supplied to the core cutting member through the opening 68 25 in the secured pin 30.

From the foregoing description, it will readily be seen that the breaking and dislodging of the bearing members is avoided by the provision of much more rugged bearing members and much more extensive bearing surfaces than is possible in the previous types of drill bits. I can do this because of the provision of the novel type of bearing members and the novel type of securing means. The locking pin 30 is protected 40 against external impediments by the internal positioning thereof. The only external contact of the member 30 is at the cutters 61, which contact tends to tighten 45 the member 30 in place.

The corkscrewing and wobbling of the drill is prevented by the supplying of the novel guiding means in the form of reaming disks 51. From the drawings it will be 50 seen that the reaming disks are disposed substantially at right angles to the boring disks and, therefore, provide contact with the wall of the hole in four places around 55 the circumference thereof. Although I have shown only one series of reaming disks, it is manifest that several series, one series above the other, might be disposed around the body 12 at varying angles so as to contact 60 with correspondingly more wall of the hole and in more places on the circumference thereof.

Any interference to the progression of the 65 drill, due to the formation of cores, is entirely eliminated by the provision of the

core cutting arrangement. By providing a combination disk drill and disk reamer, I am able to provide a disk bit which does not require after-reaming of the hole; and by providing a reamer arrangement in the form of one or more series of disks, I am able to supply a bit which has a very extensive period of operation. By positioning the reaming elements 51 at an angle with respect to the axis of rotation A—A, the rotation 75 thereof is assured as was previously explained.

I claim as my invention:

1. A disk bit comprising: a body having a central portion and a depending leg; lower bearing members carried by said depending leg; boring disks rotatably supported on said lower bearing members; upper bearing members carried by said central portion; reaming disks carried by said upper bearing members; and unitary means for retaining both said lower and upper bearing members in place. 80

2. A disk bit comprising: a body having a central portion and a depending leg; lower bearing members carried by said depending leg; boring disks rotatably supported on said lower bearing members; upper bearing members carried by said central portion; reaming disks carried by said upper bearing members; and a securing pin 90 extending into said body and contacting with said lower and upper bearing members for securing said lower and upper bearing members in place. 95

3. A disk bit as defined in claim 2 in which the lower end of said securing pin has core-removing blades formed thereon. 100

4. A disk bit as defined in claim 2 in which said securing pin has a threaded portion at the lower end which screws into said body for retaining said securing pin in place and has core-removing cutters formed on the lower end thereof. 105

5. In a bit, the combination of: a body adapted to carry a plurality of rotatable disk cutters; means supported by said body for carrying said disks; and a locking key insertable along the longitudinal axis of said body engaging said means so as to retain said means and said disks to said body, said locking key having cutting blades at one end. 110

6. A disk bit comprising: a body having a central portion and a depending leg; lower bearing members carried by said depending leg; boring disks rotatably supported on said lower bearing members; upper bearing members carried by said central portion; reaming disks carried by said upper bearing members; and unitary means extending axially into said body for retaining both said upper and lower bearing members in place. 120

7. A disk bit comprising: a body having 125

a central portion and a depending leg; lower bearing members carried by said depending leg; boring disks rotatably supported on said lower bearing members; upper bearing members carried by said central portion; reaming disks carried by said upper bearing members; and a securing pin inserted axially into said body and being threadably secured in place, said pin being arranged to secure both said lower and upper bearing members in place.

8. A disk bit comprising: a body having a central portion and a depending leg, there being a lubricating passage extending through said central portion; upper bearing members extending into said central

portion, said lubricating passage being so formed as to extend around said upper bearing members; lower bearing members extending into said depending leg; upper disks carried by said upper bearing members; lower disks carried by said lower bearing members; and a securing pin for retaining said upper and lower bearing members in place, said securing pin having a passage 25 therein which connects with said lubricating passage.

In testimony whereof, I have hereunto set my hand at Los Angeles, California, this 1st day of November, 1924.

FREDERIC W. HILD.
